UNITED STATES PATENT OFFICE.

FRED ORTHMANN, OF BROOKLYN, NEW YORK.

CORNICE SCAFFOLD.

Application filed March 14, 1922. Serial No. 543,699.

To all whom it may concern:

Be it known that I, FRED ORTHMANN, a citizen of the United States, and resident of the city of New York, borough of Brooklyn, 5 county of Kings, and State of New York, have invented a new and Improved Cornice Scaffold, of which the following is a full, clear, and exact description.

My invention relates to a scaffold, and 10 aims to provide a device of this nature particularly adapted for use in connection with cornice work.

It is a well appreciated fact that considerable difficulty has been experienced in reaching 15 a cornice for the purpose of effecting repairs, painting of the same, etc. and with this in mind my present invention aims to provide a scaffold of simple and inexpensive construction which may be utilized by a 20 repair man or by the usual householder, and by means of which an operator will be enabled to position a supporting member in such a manner that the cornice may readily be repaired.

It is a further object of this invention to 25 provide a device of the character stated capable of being disassembled so that the same may be stored in a minimum amount of space and

Among further objects of this invention is 30 that of providing a scaffold of the type described which may be readily handled by a relatively unskilled person and which will provide a structure insuring the safety of 35 this person while effecting repairs upon the cornice and parts of a building adjacent to the same.

Still further objects of this invention will 40 become apparent in the annexed specification, taken in connection with the drawings, which latter illustrate one practical embodiment of the same, and in which:

Figure 1 is a perspective view of a scaffold 45 embodying my improved construction and showing the same applied to a building.

Figure 2 is an enlarged fragmentary sectional view of a detail of construction of the 50 said scaffold.

Figure 3 is a sectional side view of the 55 device as shown in Figure 1, and

Figure 4 is a plan view of the same.

It will be seen in these views that the reference numeral 5 indicates a building having the usual cornice 6 forming a part thereof, 55 the upper surface of which cornice presents a ledge 7 upon which my improved scaffold

is supported, the latter being retained in this position in a manner hereinafter described, and by means of cables 8 having one of their ends suitably anchored to a fixed 60 portion of the building.

With a view of providing a base for the scaffold I utilize a board or plate 9 which may be attached to the ledge 7 by any suitable temporary means such as nails 10, and 65 this board carries the hinge portions 11 which extend beyond the said ledge 7. Also the board 9 carries members 12 by means of which cables 8 may be attached thereto.

Referring to the usual construction of the 70 scaffold it will be seen that the same includes a pair of preferably quadrangular frames 13, each of which is conveniently constructed of a series of angle irons secured together by bolts 14 it being noted that connecting portions 15 are provided between the frames 13 with a view of connecting the same together, and that the ends of the outer pair of connecting portions 15 are extended upwardly 75 beyond the outer frame 13, then inwardly as 80 at 16 to a point adjacent the outer edge of the ledge 7, subsequent to which they are again extended upwardly and serve to support the rack 17.

With a view of supporting the scaffold 85 proper by means of the plate 9 it will be seen that as in Figure 2 the hinge portions 11 secured to the board 9 are adapted to retain pins 18, and the latter preferably pass through openings in the portions 16 of the 90 connecting members 15, and the suspending straps 19 preferably of iron have their ends secured to the scaffold, as indicated, their bodies passing over the bodies of the pins 18.

Thus assuming that an operator desires 95 to properly position the scaffold it will be appreciated that the board or plate is positioned upon the ledge 7 in the manner aforementioned subsequent to which the body of the scaffold is placed in the position indicated 100 in dotted lines in Figure 3. When the parts are in this position it will be obvious that the pins 18 may be passed through the hinge portions 11 and through the openings in the 105 parts 16, as well as under the bodies of the straps 19. The scaffold may now be swung to the position shown in full lines in all of the figures, and it will be obvious that when the parts are in this position an operator 110 will be enabled to work with the utmost freedom along the cornice, it being under-

stood that a suitable supporting floor 20 is associated with the lowermost frame 13, and that the rack 17 acts as a retaining member for tools and supplies which may be necessary for the work being undertaken.

Thus it will be appreciated that the objects of this invention are accomplished and it will readily be understood that numerous modifications of structure might readily be resorted to without in the least departing from the scope of my claim; which are

1. A scaffold including a body comprising a plurality of quadrangular frames, connecting members extending between said frames the outermost of said connecting members being extended beyond the uppermost of said frames, an inwardly extending

portion forming continuations of each of said extended portions, and means co-operating with said inwardly extending portions 20 for supporting said scaffold.

2. A scaffold including a body comprising a plurality of quadrangular frames, connecting members extending between said frames the outermost of said connecting members being extended beyond the uppermost of said frames, an inwardly extending portion forming continuations of each of said extended portions, means co-operating with said inwardly extending portions for supporting said scaffold, and a rack attached to said inwardly extending portion.

FRED ORTHMANN.
